SCALE $\frac{3}{4}$ INCH TO THE FOOT.

Design - Iron Railing

Robert Wood

Des. 880

Robert Wood of Philadelphia, Pa.
Letters Patent No. 880. Dated Apr. 7th. 1857.

The schedule referred to in these Letters Patent and making part of the same.

Dec. 880.

To all whom it may concern:

Be it known that I, Robert Wood, of the City of Philadelphia, in the County of Philadelphia, and State of Pennsylvania, have invented and produced a new and original design for an iron railing, and I do hereby declare that the following is a full and exact description of the same.

The railing consists of cast iron braces, marked A¹, on the drawing, which are to be set into a stone coping or stone blocks and leaded in. A¹ is the front view and A², the side view of the brace. These braces carry a cast iron coping B, and a top rail C. The coping is made with two horizontal moulded bars connected by ornamental open work and is provided with cups in which the perpendicular bars stand and are leaded into; the top rail is perforated to admit the perpendicular bars and rests on a small shoulder on the brace and is riveted thereto. The perpendicular bars D, are formed in their section in the shape of a rhombus with its sides curved inwards, as seen at E, and are finished with an ornamental top.

This railing is intended for enclosing lots of any size and shape.

What I claim in this instance is the form of all the parts of the railing as above described, that is, the design as above set forth, reference being had to the accompanying drawing which is an accurate representation of the same at a scale of three quarters inch to the foot.
